SPOOL NEEDLE CUSHION

Frederick Goertz, South Orange, N. J.

Application February 17, 1937, Serial No. 126,139

12 Claims. (Cl. 223—109)

The invention herein disclosed relates to needle and pin cushions for attachment to thread carrying spools.

The objects of the invention are to provide a cushion of this type, which may be inexpensively produced, be readily applied to thread spools and form, when so attached, a convenient, practical and ornamental holder for needles and pins.

Further objects are to provide such a cushion, which can be folded in substantially flat condition to take up small space when not in use and which may be quickly unfolded to mount it at the end of the spool.

The foregoing and other desirable objects are obtained by novel features of construction, combinations and relations of parts, all as hereinafter described, illustrated in the accompanying drawing and broadly covered in the claims.

In the drawing there is illustrated one practical embodiment of the invention, but it is to be understood that the structure may be modified and changed all within the intent of the invention as hereinafter defined.

Fig. 1 is a perspective view showing the cushion in use applied to the end of a spool.

Fig. 2 is an edge view showing the cushion in a folded condition.

Fig. 3 is an edge view, turned at an angle and showing the spring loop lowered or opened out for insertion in the bore of the spool.

Fig. 4 is a plan view looking at the underface of the article.

Fig. 5 is an enlarged cross-sectional view of the device.

In the form of the invention illustrated, the pad or cushion is made up of a layer or layers 1, of suitable material, such as felt mounted so that it may be located over the bore or passage through the center of the spool 8.

In this particular disclosure, there are two such layers, one of them at the outer face of the cupped shell 9, held by an outer cover 10, of celluloid, paper or the like, and the other at the inner face of such shell held by a washer 11, of cardboard or the like. The parts are held together in the relation described by a cupped back plate 12, the flange 13, of which is forced inside the corresponding flange 14, of the shell.

In Fig. 5, the outside cover layer 10 is shown as extended about the edge of flange 14, and as caught in this relation by the inserted flange 13 of the back plate and the latter is indicated as dished inwardly, approximately to the curvature of the convex shell member 9, so as to bow and

firmly clamp the washer and the inner layer of pad material against the inside face of the shell.

The cushion carrying element thus far described is removably attached to the spool head in the construction here shown by a spring loop 5, consisting of a doubled length of wire having outwardly extending acutely bent ends 16, caught beneath the inwardly dished face of the back plate 12, and the cardboard washer 11. The pressure of closing the parts together forces these outwardly extended ends of the wire into the face of the yieldable washer forming bearings for them and the acute angle of these ends causes them to hook over the inwardly dished face of the backplate sufficiently to prevent such ends from readily coming loose. This anchorage of the ends of the wire also stiffens the extended loop of the wire sufficiently to make it act as a spring stiff enough to hold the cushion securely enough for all practical purposes. This construction also prevents the spring loop from pulling loose from the cushion structure when the latter is pulled away from the spool. These outwardly angled ends also permit the loop being hinged bodily as in Fig. 2 toward the back of the cushion disc, 25 enabling the article to be packed in substantially flat condition. This hingeable construction also permits the loops to adjust themselves if the inner ends should contact when two of the needle holders are applied to opposite ends of the same 30 spool.

The device consists of but few inexpensive parts, is easy to manufacture and the parts are secured in the simple act of assembly. The needle cushion lies flat against the end of the spool taking up small space and really enhancing the appearance of the spool. The cover material 10, may be colored to match the color of the thread and may carry ornamentation, advertising matter or equivalent. This cover material instead 40 of being applied as a separate sheet of celluloid, paper or the like, may be painted on, or applied in the form of a lacquer, varnish or the like.

What is claimed is:

1. A needle holder for spools, comprising reversely cupped telescopically engaged centrally perforated discs, needle cushion material over the central perforations of said discs and a spring loop having outwardly angled ends located between said cupped discs. 50

2. A needle holder for spools, comprising reversely cupped telescopically engaged centrally perforated discs, needle cushion material over the central perforations of said discs, a spring loop having outwardly angled ends located be- 55

tween said cupped discs and a washer of yieldable material between the discs and engaged with the angularly bent ends of said spring loop.

3. A needle holder for spools, comprising 5
versely cupped telescopically engaged centrally perforated discs, needle cushion material over the central perforations of said discs, a spring loop having outwardly angled ends located between said cupped discs, a washer of yieldable 10
material between the discs and engaged with the angularly bent ends of said spring loop, the needle cushion material being engaged between said washer and the inside face of one of said discs.

15. 4. A needle holder for spools, comprising re-
versely cupped telescopically engaged centrally perforated discs, needle cushion material over the central perforations of said discs, a spring loop having outwardly angled ends located be- 20
tween said cupped discs, a layer of cover material over the face of the outer disc and caught at its edge between the telescopically engaged rims of the two cupped discs.

25. 5. A needle holder for spools, comprising re-
versely cupped telescopically engaged centrally perforated discs, needle cushion material over the central perforations of said discs, a spring loop having outwardly angled ends located be- 30
tween said cupped discs, a layer of cover ma-
terial over the face of the outer disc and caught at its edge between the telescopically engaged rims of the two cupped discs and the needle cushion material including a pad held between the outer face of said disc and said layer of cover 35
material.

30. 6. A needle holder comprising a centrally per-
forated cupped shell having a rearwardly flanged 40
rim, a pad of needle cushion material carried by said shell across the central perforation, a spring loop projecting from the back of said shell and having outwardly turned ends and means en-
gaged with the backwardly flanged rim of said shell for securing said outwardly bent ends of the spring loop.

45. 7. A needle holder, comprising centrally per-
forated front and back plates, one having a flange engaged with the rim of the other, needle cushion material carried by said plates and ex-
tending over the centrally perforated portions 50
of the same and a rearwardly extending spring loop having outwardly angled ends held between said plates.

8. A needle holder, comprising centrally per-
forated front and back plates, one having a flange engaged with the rim of the other, needle cushion material carried by said plates and ex-
tending over the centrally perforated portions 5
of the same, a rearwardly extending spring loop having outwardly angled ends held between said plates and a yieldable spacing washer between the plates and engaged with said outwardly angled ends of said spring loop. 10

9. A needle holder, comprising a centrally per-
forated disc-like support, needle cushion mate-
rial carried by said support over the central perforation and a spring loop attached to said support and projecting rearwardly through the 15
central perforation in position to enter the bore in a spool of thread.

10. A needle holder, comprising a centrally per-
forated disc-like support, needle cushion mate-
rial carried by said support over the central 20
perforation, a spring loop attached to said sup-
port and projecting rearwardly through the central perforation in position to enter the bore in a spool of thread, said spring loop having the 25
ends of the same at opposite sides of said central perforation pivotally secured to said support and whereby said spring loop may be hinged more or less flat against the back of the support.

11. A needle holder, comprising a convexed sup-
port approximately the diameter of the spool 30
end and having a central perforation to register 35
with the bore of the spool and a wide annular area about said central perforation for advertising matter, ornamentation or the like, a pad of needle cushion material carried by said support and extending over said central perforation and spring mounting means projecting from the back of said support to frictionally engage in the bore of a spool and having angled ends caught within 40
said support.

12. A needle holder, comprising a disc-like mem-
ber of approximately the diameter of a spool of 45
thread, said member having a central perforation to align with the bore of a spool and having a flange rim, a spring mounting member having outwardly angled portions located within said flanged rim and projecting portions extending through the central perforation and pin cushion material carried by said member and extending across the central perforation. 50
